CHENEY KILBURN, OF PHILADELPHIA, PENNSYLVANIA, ASSIGNOR TO
KILBURN & GATES, OF SAME PLACE.

Design No. 4,151, dated June 14, 1870.

DESIGN FOR BOXES FOR THE TOPS OF BUREAUS.

The Schedule referred to in these Letters Patent and making part of the same.

I, CHENEY KILBURN, of Philadelphia, county of Philadelphia, State of Pennsylvania, have invented and produced a new and original Design for Boxes for the Tops of Bureaus, of which the following is a specification.

On reference to the accompanying drawing—

Figures 1 and 2 are perspective views of boxes made in accordance with my design;

Figures 3 and 4, plan views of the same; and

Figure 5, a sectional view showing the design of the molding or finish for the edge and lid of the box.

My design is for the boxes which are usually placed upon the tops of bureaus for the support of the standards to which the glass is secured; and

The design consists principally in making such boxes of an oval or elliptical form, instead of square, angular, or semicircular, as they have been made heretofore.

The box represented in figs. 1 and 3 is formed on a flat, oval, or elliptical curve, and is made of sufficient length to support both of the standards of the bureau, while the box shown in figs. 2 and 4, which

is considerably shorter, is intended to support one of the standards only, and is of a sharper curve, similar to that of an oval or ellipse divided on its short axis.

The molding or finish for the edge and lid of the box forms, also, a part of my design, and is of the character clearly represented in the sectional view, fig. 5.

Claims.

1. A box for the tops of bureaus, formed on an oval or elliptical curve, substantially as described and as represented in and by the accompanying drawing.

2. The design for the molding or finish on the edge of the said box and lid, substantially as shown in fig. 5 of the drawing.

In testimony whereof I have signed my name to this specification in presence of two subscribing witnesses.

CHENEY KILBURN.
